UNITED STATES PATENT OFFICE

CHESTER J. DECKER, OF TORONTO, ONTARIO, CANADA

LAMP SUPPORT

Application filed February 9, 1929. Serial No. 338,867.

The principal objects of this invention are to provide a means of supporting a lamp from a bed frame in such a manner that it may be readily adjusted to various positions and held securely in the adjusted position in a simple and effective manner so that it cannot be accidentally dislodged but so arranged that it may be easily and quickly moved out of the way without being removed from its support.

A further and very important object is to provide a support which may be extended to an extraordinary distance, either vertically or horizontally to facilitate its use particularly for hospital purposes and further to provide a support which may be readily utilized for the support of utensils required in hospital service.

The principal features of the invention consist in the novel arrangement of an upright guide upon a bed frame whereby a supporting member is adjustably mounted and the adjustable member is capable of universal movement to support a lamp in a raised or horizontally extended position.

In the accompanying drawings Figure 1 is an elevational view of the end frame of a bed illustrating the preferred form of application of the invention as applied to a lamp support.

Figure 2 is a side elevational view of Figure 1.

Figure 3 is a side elevational view showing the lamp support extended in a horizontal position.

Figure 4 is an enlarged longitudinal sectional detail of a portion of the extensible lamp supporting post.

Figure 5 is an enlarged perspective detail showing the hinge joint of the extensible post and the means for locking the post in adjusted positions.

Figure 6 is a perspective detail of a support member to be used in the tubular lamp arm support.

In the form of the invention herein shown the end frame 1 of the bed is of the usual type of tubular structure having a plurality of vertical tubes 2 extending downwardly from the horizontal top portion 3 to a cross tube 4.

One of the vertical tubes 5 extends through the top of the top tube 3 and has secured to its upper end or forming part thereof a longitudinally slotted chuck member 6, provided with a threaded portion 7.

A chuck sleeve 8 threaded on to the portion 7 is provided with a tapered inner wall 9 to engage the tapered surface of the slotted chuck member. This sleeve is provided with a suitable head end 10 which enables it to be readily grasped by the hand for tightening or loosening.

The lower end of the tube 5 may extend below the cross tube 4 if such length is desired.

A long tube or rod 11 is slidably arranged within the tube 5 and extends through the top of the chuck sleeve. This tube is provided adjacent to its lower end with a hinge joint 12 which allows the major portion of the length of the tube to be bent into right angular position in relation to the tube 5 to extend horizontally and the joint is so made that the extension portion rests in a horizontal position.

The upper end of the tube 11 has secured therein a length of fibre rod 13 which forms an insulating connection to the tubular member 14 to which is secured a flexible lamp-supporting arm 15.

The member 14 is provided with a hollow lateral extension 16 through which the electric wires 17 are connected to the lamp socket. A suitable shade 18 is provided on the end of the flexible arm to enclose the lamp.

It will be seen that when the lamp-supporting tube 11 is in the vertical position illustrated in Figures 1 and 2 the flexible arm 15 may be bent into any desirable position to throw the light from the lamp downwardly and the arm may be swung horizontally by allowing the tube 11 to rotate in its support. It may, however, be fastened securely in any desired position by tightening the chuck sleeve 8 so that the slotted chuck member will grip and hold the tube.

If it is desired to raise the lamp, this may be done by loosening the chuck sleeve and simply pulling upwardly upon the tube 11 and then a slight turn of the chuck sleeve will hold it.

The lamp is available in this position either for reading or for turning aside to throw the light directly upon a table or for use of a physician or nurse examining the head, shoulders or back of a patient. If a body examination is to be made, the lamp support tube 11 may be raised upwardly until the hinge joint 12 is raised above the chuck sleeve, when it may then be swung to a horizontal position as illustrated in Figure 3 and the horizontally extending member may be locked securely or swung from side to side pivoting in the support 2 and the flexible lamp arm on the end of this tube enables the adjustment of the light to any desired position over the patient.

It is frequently found desirable to extend a utensil in an elevated position above a bed and for this purpose the lamp tube may be removed and a rod 19, as shown in Figure 6, carrying a support at its upper end may be inserted into the vertical tube 5 and secured at any desirable height above the bed.

The advantages and uses of a device such as described are manifold and while its uses have been particularly emphasized in regard to hospital service, it will be readily appreciated that the device may be applied with advantages in other fields.

It has been stated that it is preferable to utilize the vertical tube structure of the bed but it must be understood that the vertical supports may be attached to the frame in other ways and while a tubular support is preferable, it will be readily appreciated that other forms of vertical supports might be devised without departing from the spirit of this invention.

What I claim as my invention is:

1. A support for lamps or the like, comprising in combination a tubular support, an extensible member formed of a plurality of relatively adjustable sections each adapted to engage the inner wall of said tubular support in guiding contact, clamping means carried by said tubular support adapted to clamp each of said sections rigidly to said tube in adjusted relation thereto, a lamp mounted on the outer of said adjustable sections, an insulating section carried by the said outer section, and current-conducting wires leading to said outer section and lamp beyond said insulating section, said insulating section being adapted when said sections are housed in said tubular member to extend partly thereinto to be engaged by said clamping means and effecting an insulation between said tubular support and clamping means and the source of current when said adjustable member is in either its housed or extended position.

2. In a lamp support, in combination, a bed frame having a tubular member open at the top, a member formed of a plurality of jointed sections each of equal diameter correspond-

ing substantially to the internal diameter of the tubular member whereby said sections are adapted to each engage the inner wall of said tubular member in guiding contact, an insulating extension on one of said sections adapted to project beyond the tube end when the sections are housed therein, a lamp fixture mounted on said insulating extension having wires leading thereto beyond said extension, and a common clamping means arranged on said tubular member for co-operating with and locking any one of said jointed sections in rigid relation to said tubular member.

3. In combination, a bed frame having a vertical tube open at the top, a clutch mounted on the upper end of said tube, a rod slideable in said tube and having a hinged portion at its lower end, a rod of insulating material rigidly secured to the upper end of the aforesaid rod, a hollow member rigidly secured to the upper end of said insulating rod and having an opening in the side thereof, a lamp holder mounted on the upper end of said hollow member, and electric wires leading through said hollow member and said lamp holder.
